GOVERNOR

Robert E. Boyden, Los Angeles, and Edward P. Drake, Glendale, Calif., assignors to Clary Multiplier Corporation, Los Angeles, Calif., a corporation of California

Application November 26, 1945, Serial No. 630,914

7 Claims. (Cl. 200—80)

1

This invention relates to speed governors and has particular reference to governors for maintaining electric motors at substantially constant speed under varying load conditions.

Heretofore, governors of the above type have generally utilized the differential action between centrifugal force acting on a governor flyweight and a restraining force in the form of a spring, to control the speed of an electric motor by opening and closing the switch contacts in the motor circuit by amounts in proportion to the differential action produced.

Also, in the last several years governor manufacturers have tended to reduce the mass of the flyweights or similar centrifugally operated control means in order to reduce the lag in control introduced by the inertia and momentum of such parts. At the critical control speed of governors of such types, the small amount of movement of the flyweight mass necessary to open and close the contacts in order to control the speed, and the relatively small amount of mass available to cause a controlling action, introduced a detrimental arcing effect since the contacts are separated only slightly. This arcing effect is accentuated by reason of the fact that since even the maximum separation of the contacts is only a minute amount, the arc thus produced still maintains a considerable current carrying capacity. As a result the contacts, instead of completely closing, tend to merely create an arc and then vary the resistance of the arc by varying the separation of the contact points. Such arcing necessitates arc damping means such as condensers, etc. to reduce as far as possible the tendency of the contact points to arc. Furthermore, such arcing causes loss in electrical power and radio interference as well as deterioration of the contacts.

It therefore becomes the principal object of the present invention to reduce arcing in a motor governor.

A further object of the invention is to obviate the necessity of a condenser or other arc damping means for a motor governor.

A further object is to reduce radio interference due to a motor governor.

A further object is to reduce electric power losses in a governor.

A further object is to produce the frequency at which the contacts of a governor are operated whereby to prolong the life of the contact points.

A further object is to provide an arrangement of governor elements whereby the frequency of switch contact action is automatically regulated

2

so that when the motor is running idle a minimum frequency of contact action is obtained to decrease contact deterioration and when the motor is running under load the frequency of contact action is automatically increased to maintain a substantially uniform motor speed.

A further object of the invention is to provide a simple and compact governor which is inexpensive to manufacture.

The manner in which the above and other objects of the invention are accomplished will be readily understood on reference to the following specification when read in conjunction with the accompanying drawing;

10 15 Fig. 1 is a side view partly in section, of an electric motor governor embodying the present invention.

Fig. 2 is a front view of the motor governor and is taken along the line 2—2 of Fig. 1.

20 25 Fig. 3 is a transverse sectional view of the flyweight unit and is taken along the line 3—3 of Fig. 1.

Fig. 4 is a sectional view of a modified form of flyweight unit.

25 30 Fig. 5 is a sectional view through the governor switch arrangement and is taken along the line 5—5 of Fig. 2.

Fig. 6 is a schematic diagram of an exemplary circuit showing the connection of the motor governor to an electric motor.

35 Fig. 7 is a modified form of switch which may be incorporated in the governor of the present invention.

Referring to the drawing, the governor, generally indicated at 10, is illustrated as comprising a main bracket 11 attached by screws 12 (Fig. 2) to the end casing of a motor 13.

40 The flyweight unit of the governor comprises a hub 14 attached by a pin 15 to the armature shaft 16 of the motor. A flyweight bracket 17 is secured to the hub and has mounted thereon on diametrically opposed sides of the motor shaft, a pair of transversely extending pins 18 which pivotably support flyweight levers 19 for movement about axes extending to right angles to the axis of rotation of the flyweight unit. A ball 20, freely movable in an axially extending hole in the hub 14, is adapted to be forced along the axis of the motor by the tails of the levers 19.

45 50 It will be noted that the center of gravity of each of the levers 19 lies to the right (Fig. 1) of its pivotal axis so that, as the motor accelerates, the tails of the levers 19 force the ball 20 outwardly against an ear 22 located at one end of a lever 21. The latter is pivoted on a pin 23 (Figs. 1

and 2) securely mounted on an upturned ear of the main bracket 11. An ear 24 on the lower end of lever 21 overlies a plunger 25 (Fig. 5) of a switch generally indicated at 26.

The switch 26 comprises a body 27 of insulating material attached by screws 28 to the bracket 11. A leaf spring 29 of electrically conductive material is attached at one end by a screw 30 to an electric terminal which is connected by screw 31 to a conductor 32. At its free end 29, the leaf spring has a contact 130 normally engaging a stationary contact 33 secured as by screw 34 to a second terminal to which is attached a second conductor 36.

The spring 29 comprises a main section 37 which extends from the screw 30 and is biased toward the contact 33. One or more toggle sections 38 of the spring are integrally formed or attached at 39 to the main section and are bowed under compression, being held at their free ends by a fulcrum block 39 which is also held in place by the screw 30.

It will be noted that the fulcrum points of the toggle sections 38 are normally below a line passing through the point 39 and the point of attachment of the spring to the screw 30. Thus, the vertical component of force (as viewed in Fig. 5) exerted by the toggle section 38 normally aids the biasing effect of the main section 37 to press the spring into intimate engagement with the contact 33. Whenever the plunger 25 is pressed inwardly against the action of the main portion 37, the latter will move downward against its own biasing effect as well as against the toggle action of sections 38 until the section 37 passes below the fulcrum point of section 38. At that time, the toggle sections 38 will exert their vertical component of force in a downward direction, aiding the plunger 25. However, the downward component of force is not sufficient to overcome the upward biasing effect of the section 37 so that upon release of pressure upon the plunger 25 the contact spring will assume its normal closed condition illustrated in Fig. 5.

The above described switch is commercially known and available under the name micro-switch, being disclosed and claimed in the patent to P. K. McGall, Number 1,960,020. However, it is to be understood that other types of switches operating under the same basic type of toggle action may be employed without departing from the scope of the present invention.

It will be seen from the above that as the speed of the motor approaches a definite amount, the flyweight levers 19 will rock about their axes, pressing the ball 20 outward to rock lever 22 and thereby cause the plunger 25 to press downward against the spring section 37. As the force against the spring section 37 increases, it will gradually overcome the bias effect of the spring as well as the force exerted by the toggle sections 38 and will finally force the spring into a lowermost position, breaking the circuit. This final action will occur in an abrupt movement, thus reducing the tendency of an arc to form between the contacts. As the speed of the motor is reduced due to breaking of the circuit between the contacts the reduction of centrifugal force developed by the flyweight levers 19 will permit the spring 37 to again assume its closed position. This closing action of the spring will again occur in an abrupt movement due to the toggle action of the spring section 38.

Means are provided for adjusting the governor to control the speed of the motor as desired.

Referring to Fig. 1 an adjusting screw 40 is threaded in a collet 41 integrally attached to the bracket 11. Located between the ends of screw 40 and the ear 22 of lever 21 is a compression spring 42 which may be adjusted by the screw to aid the spring section 37 in opposing the action of the flyweight levers. Thus, the speed of the motor may be increased by increasing the pressure of the spring 42 against the lever 21, requiring greater centrifugal force to be developed in the flyweight levers by virtue of a higher rotational speed in order to open the switch contacts.

A spring 44 is inserted between the ear 22 of lever 21 and the bracket 11 to oppose the spring 37 so that the screw 40 may be adjusted to effect either an aiding or opposing action upon the biasing spring section 37 to vary the controlling speed of the motor throughout a relatively wide range of speed.

It will be noted that the spring 44 is considerably weaker than the compression spring 42 since the former is utilized during control of the governor at relatively low speeds wherein the centrifugal force developed by the flyweight levers is correspondingly weaker. This combination of springs results in a more uniform control throughout the various possible speed ranges of the motor.

During operation of the motor and governor under no-load conditions the switch contacts are opened and closed at a relatively low frequency, such frequency being dependent upon the amount of revoluble mass or flywheel effect of the motor armature and other rotatable parts connected thereto. However, under load conditions, this frequency is increased and such increase is proportional to the increase in load. This feature results in a considerable saving in contact deterioration.

Fig. 6 illustrates an exemplary connection of the governor to the motor, the latter being illustrated as of the series type comprising a field winding 13a and an armature 13b connected in series with the contacts 33 and 130. A resistance 45 may be shunted across the contacts to reduce the voltage drop during opening and closing of the contacts. The latter is illustrated in Figs. 1 and 2 as being supported in the governor unit by ears 46 extending from the brackets 11.

Fig. 7 illustrates a modified form of switch which may be used in lieu of the switch 26 (Fig. 5). This switch comprises a base 27a of insulating material to which is attached, by a screw 140, a flexible terminal 135. The forward end of the terminal is biased downward a slight amount and carries a contact 33a. A second contact 130a is mounted on a pivotal piece 131 fulcrumed on a pivot block 39a suitably attached to the base 27a, the block 39a also forming the second terminal for the switch. A biasing spring 132 is tensioned between the base and the piece 131 to normally hold the contacts in closed condition.

A spring 133 is tensioned between the block 39a and the outer portion of the piece 131 to exert a toggle action on the piece. That is, in the closed condition of the switch, as illustrated in Fig. 7, the center line of the spring 133 extends above the fulcrum point of the piece 131, thus exerting an upward force, aiding the spring 132.

When the piece 131 is forced downward by a plunger 25a the flexible terminal 135 will cause contact 33a to follow the contact 130a until the piece 131 moves to a position wherein the center line of spring 133 passes below the fulcrum point of the piece. The contact 130a will now leave

contact 33a in a somewhat abrupt manner in view of the reversal of the action of spring 133. Although the spring 133 will now oppose the tension of spring 132 it will not quite overcome the latter so that when pressure on plunger 25a is released the switch will reassume its closed condition. A limit stop may, if desired, be provided to prevent downward movement of the piece 131 beyond a definite limit. For this purpose, a foot 141 formed on the lower end of the terminal 133 may be extended laterally to limit downward movement of the piece 131.

Fig. 4 illustrates a modified form of flyweight unit in which the controlling effect of the flyweight levers 19 may be adjusted. In this figure all elements similar to those shown in Fig. 1 are indicated by the same reference numerals. Threadably attached to the outer ends of the flyweight levers 19 are adjustable screws 47. By adjusting the screws 47 outwardly a greater amount of centrifugal force is developed and therefore a more positive control action is effected by the flyweight levers. The provision of this adjustment enables a minimum flyweight mass to be used whereby to obtain a readily responsive controlling action while at the same time providing a governor which will be effective over a wide range of speed, particularly at low speed since the centrifugal force developed in any rotatable body is proportional to the square of the speed of such body.

We claim:

1. A motor speed control device, comprising: electric contact means for controlling a circuit to a motor, said contact means being movable between open and closed positions, spring means normally holding said contact means in closed position, a governor device adapted to be rotated by said motor and including means displaceable by centrifugal force during rotation thereof for opening said contact means; a snap-over spring means coacting, in a first position thereof, with said first-mentioned spring means, to close said contact means, means operable by said displaceable means upon a predetermined displacement thereof by centrifugal force for causing said snap-over spring means to move from said first position to a second position, said snap-over spring means being effective to substantially abruptly move between said two-mentioned positions, a third spring means opposing the action of said first-mentioned spring means and aiding said governor device and said second spring means in opening said contact means, and means for adjusting the effective force of said third spring means.

2. A motor speed control device, comprising: electric contact means for controlling a circuit to a motor, said contact means being movable between open and closed positions, spring means normally holding said contact means in closed position, a governor device adapted to be rotated by said motor and including means displaceable by centrifugal force during rotation thereof for opening said contact means; a snap-over spring means coacting, in a first position thereof, with said first-mentioned spring means, to close said contact means, means operable by said displaceable means upon a predetermined displacement thereof by centrifugal force for causing said snap-over spring means to move from said first position to a second position to open said contact means, said snap-over spring means being effective to substantially abruptly move between said two-mentioned positions, third spring means op-

eratively connected to said displaceable means, and means for adjusting the effective force of said third spring means to selectively aid or oppose said governor device.

3. In an electric motor governor having electric contact means for the circuit of said motor, said contact means being movable between open and closed positions, and a governor device adapted to be rotated by said motor and including means displaceable by centrifugal force during rotation thereof; a leaf spring supported in cantilever fashion adjacent one end thereof and adapted to flex at the other end thereof to open and close said contact means, a spring strip connected at one end to the flexible end of said leaf spring, said spring strip being bowed in longitudinal compression and being pivoted at the other end thereof at a point between the ends of said leaf spring, said leaf spring normally assuming a position on one side of the dead center of the spring assembly formed by said leaf spring and said spring strip whereby to close said contact means, means operable by said displaceable means upon a predetermined displacement thereof by centrifugal force for acting on said leaf spring between said point of support thereof and said pivot point of said spring strip, whereby to cause said spring assembly to open said contact means with a snap action, a second spring means operatively associated with said spring assembly for exerting a biasing effect thereon, and means for adjusting the force of said second spring means to selectively either aid or oppose the action of said device and thereby affect the action of said spring assembly in opening and closing said contact means throughout the range of movement thereof.

4. A motor speed control device comprising: a bracket adapted to be secured in fixed relation to a motor; a centrifugal governor adapted to be driven by said motor and including flyweight means responsive to centrifugal force; a normally closed switch mounted upon said bracket; a lever; means pivotally mounting said lever upon said bracket at a point intermediate the ends of said lever, one arm of said lever being engageable with said switch for actuating said switch to its open position; a spring connected with the other arm of said lever and continuously biasing said lever in a direction tending to allow opening of said switch, said other arm being operable by said flyweight means to actuate said lever in the same direction as said spring; and a second spring acting on said lever yieldably opposing the force of said flyweight means and tending to actuate said lever in a direction to allow closing of said switch.

5. A motor speed control device comprising: a bracket adapted to be secured in fixed relation to a motor; a centrifugal governor adapted to be driven by said motor and including flyweight means responsive to centrifugal force; a normally closed switch mounted upon said bracket; a lever; means pivotally mounting said lever upon said bracket at a point intermediate the ends of said lever, one arm of said lever being engageable with said switch for actuating said switch to its open position; a spring connected with the other arm of said lever and continuously biasing said lever in a direction tending to allow opening of said switch, said other arm being operable by said flyweight means to actuate said lever in the same direction as said spring; a second spring acting on said lever yieldably opposing the force of said flyweight means and tending to actuate said lever

in a direction to allow closing of said switch; and means carried by said bracket for adjusting the force of said second spring.

6. A motor speed control device comprising: a bracket adapted to be secured in fixed relation to a motor; electric contact means for controlling a circuit to said motor and mounted on said bracket, said contact means being movable between open and closed positions; spring means normally holding said contact means in closed position; a centrifugal governor adapted to be driven by said motor and including means displaceable by centrifugal force during rotation thereof; a lever; means pivotally mounting said lever upon said bracket at a point intermediate its ends; one arm of said lever being operable by said displaceable means to cause the other arm thereof to move said contact means to open position; a snap-over spring means coacting, in a first position thereof, with said first-mentioned spring means to close said contact means, and coacting, in a second position thereof, with said displaceable means upon a predetermined displacement thereof to open said contact means, said snap-over spring means being effective to substantially abruptly move between said two-mentioned positions; a spring connected between said lever and said bracket and continuously biasing said lever in a direction tending to open said contact means; a second spring acting on said lever yieldably opposing the force of said displaceable means and said first-mentioned spring; and means carried by said bracket for adjusting the force of said second spring.

7. A motor speed control device, comprising: electric contact means for controlling a circuit

to a motor, said contact means being movable between open and closed positions, spring means normally holding said contact means in closed position, a centrifugal governor adapted to be rotated by said motor and including flyweight means displaceable by centrifugal force during rotation thereof for opening said contact means; a snap-over spring means coacting, in a first position thereof, with said first-mentioned spring means, to close said contact means, means operable by said flyweight means upon a predetermined displacement thereof by centrifugal force for causing said snap-over spring means to move from said first position to a second position, said snap-over spring means being effective to substantially abruptly move between said two-mentioned positions, a third spring means opposing the action of said first-mentioned spring means and aiding said governor device and said second spring means in opening said contact means, and a weight element carried by said flyweight means and adjustable relative thereto to vary the centrifugal force effective during rotation of said flyweight means.
